FLUID FUEL BURNER IGNITION CONTROL

Ira E. McCabe, Chicago, Ill.

Application June 12, 1939, Serial No. 278,673

17 Claims. (Cl. 158—28)

This invention relates to improvements in electrically operated and controlled fluid fuel burning devices and more particularly to a control for the operation of an electrical ignition device actuated by the pressure of the fluid fuel.

It is an object of this invention to improve a fluid fuel burner ignition control, such as described in this applicant's prior Patent No. 2,140,708, December 20, 1938, wherein briefly, the 5 operation of an ignition switch is controlled by the conjoint action of a fuel pressure responsive means and an electro-thermal timing mechanism being adapted to open the ignition switch a predetermined time after the starting of the burner 10 mechanism but dependent upon the pressure means responding to the establishment of a predetermined fuel pressure before such action of the timing mechanism can result in opening the switch. This improvement consists in providing such a structure with means which will automatically adjust the operation of the ignition control to compensate for changes in the pressure of the fuel delivered to the fuel burner where- 15 by a substantially constant differential is main- 20 tained between the pressures which operate upon the pressure responsive means and those main- 25 tained at the burner.

It is another object of this invention to so arrange the electro-thermal switch operating mechanism of such an ignition control in combination with an oil burner motor control that when the burner motor control stops the motor it will 30 reset the ignition control to insure an ignition period at each starting of the burner motor.

With these and other objects in view, reference 35 is made to the accompanying sheets of drawings which illustrate a preferred form of this invention, with the understanding that detail changes may be made without departing from the scope 40 thereof.

In the drawings:

Figure 1 is a schematic view illustrating the application of this invention to a pressure type oil burner forming a part of a domestic heating system, including a wiring diagram therefor including an enlarged wiring diagram of the instrument panel projected from the panel casing as it appears upon the oil burner.

Figure 2 is an enlarged detail view in front elevation of the instrument panel, with the side walls of the cover shown in section, and illustrating the construction and wiring connections of this improved ignition control in association 50 with a burner motor control.

Figure 3 is an enlarged top plan view of this improved ignition control.

Figure 4 is a view in end elevation of Figure 3, looking at the right end thereof, and with parts broken away and partly in section.

Figure 5 is a detail view of the ignition control shown in Figure 2 with parts broken away and partly in section with the ignition switch in closed position.

Figure 6 is a similar view with the ignition 10 switch open.

Figure 7 is a view in rear elevation of Figure 5.

In some forms of electrically operated and controlled fluid fuel burning devices, such as oil burners forming a part of domestic heating systems, 15 the fluid is supplied under pressure to the burner nozzle and an electrical igniter is provided to ignite the fuel during an ignition period when the igniter is energized.

An ignition control for creating the ignition 20 period is disclosed in this applicant's prior Patent No. 2,140,708, December 20, 1938, which is partially operated by the fuel pressure and the period of ignition discontinued by the passage of the current through the igniter or ignition circuit 25 for a predetermined time. Such a control employs an electro-thermal means for opening the ignition circuit and may be so adjusted that the fuel pressure responsive means acts only when a predetermined pressure is exceeded to cause 30 the opening of the ignition switch and upon a drop in the predetermined pressure to restore the ignition circuit irrespective of the operative state 35 of the electro-thermal means.

In the pressure type oil burners, the normal 40 operating pressure maintained in the burner nozzle is usually about 100 pounds per square inch and the capacity of the various sizes of nozzles in gallons per hour is based upon the delivery of fuel at this pressure. Frequently it is desirable 45 to increase or decrease the burner flame in accordance with the demands of particular heating systems and this can be accomplished, within certain limits without changing the size of the nozzle, by varying the pressure of the fuel. The operating pressure of the fuel may be varied by adjusting the pressure regulating device employed in all pressure burners interposed between the fuel pump and the nozzle to maintain a constant pressure at the nozzle.

When the fluid fuel burner ignition control of Patent No. 2,140,708, is employed with a pressure type oil burner and the adjustment of the pressure regulator is changed to adapt the burner mechanism to the demands of a particular heat- 55

ing system, as above described, a compensating change must be made to the operating mechanism of the ignition control. While such manual adjustments may be made in the said patented 5 ignition control, failure to make them might result in a failure to provide ignition upon a delivery of oil at the nozzle following an extinguishment of the burner flame, as is possible where a drop in fuel pressure due to a leak or pump 10 failure causes extinguishment of the flame, but is insufficient to operate the ignition control.

The embodiment of the invention illustrated upon the accompanying drawings provides a pressure responsive ignition control which will automatically adjust itself to compensate for variations made in the pressure regulating device. 15 Figure 1 is a diagrammatic illustration of an oil burning heating system in which a pressure type of oil burner O of a commercial form is installed 20 in a domestic heating furnace F, located in the basement of a dwelling. The wires L, L' from the commercial source of electricity pass through a hand switch H to an instrument panel I, located on the rear of the oil burner under the cover C. 25 The wire L preferably passes through a commercial boiler control B on its way to the panel. The wires L, L' are connected through the panel to the burner motor M and to the ignition transformer I, as will hereinafter be described. A 30 room thermostat T of commercial form for controlling the operation of the oil burner is shown in a room above.

As shown in the wiring diagram in Figure 1 and in the detail of the instrument panel I is 35 shown in Figure 2, the wire L from the commercial source of electricity is connected to the binding post 2 which is connected by the wires 3 through a normally closed safety switch SS and through the windings of the primary coil PC of a 40 commercial type of repulsion relay to the binding post 4 to which the wire L' is connected. The repulsion relay includes a secondary coil SC. The windings of the secondary coil SC are connected to binding posts 7 and 14, located in a terminal 45 post supporting plate above the relay. Posts 6 and 7 are connected by wires 5 to the room thermostat T while posts 6 and 14 are connected to a safety switch electrical resistance heater SH which cooperates with a thermostatic arm 12 to 50 release the normally closed safety switch SS to open, upon energization of the heater, for a predetermined time. The secondary coil SC is mounted upon one end of a pivoted arm 8 which carries the motor switch MS so mounted on the 55 other end that the weight of the dead or deenergized coil SC will open the switch, as shown in Figure 2. With the circuit closed through the relay primary coil PC and the room thermostat calls for heat, the circuit through the secondary 60 coil SC of the relay is closed and the coil is repelled to close the motor switch MS, as shown in Figure 1. The circuit established by the closing of the room thermostat through wires 5 passes through post 6, resistance heater SH, post 14, 65 windings of the secondary coil SC to post 7. With the motor switch closed the current from wires 3 divides and passes through wires 9, binding post 10, through the burner motor M, and binding post 11 to binding post 4 which is connected to wire 70 L'. When the room thermostat closes the secondary coil circuit, the safety switch heater SH is also energized and after a predetermined time, provided for the purpose of establishing combustion, will operate to cause the opening of the safety switch SS and stop operation of the burner, 75

In order to allow the safety switch SS to remain closed after establishment of the burner flame within the predetermined period, a shunt circuit is provided to shunt out the heater SH. In this instance a flame responsive switch FR is interposed in a shunt circuit formed by wires 13 leading from binding post 6 in the secondary circuit through the switch FR and back to the binding post 14 in the secondary circuit, shunting out the heater SH. The flame responsive switch is preferably constructed in accordance with this applicant's prior application Serial No. 124,982, filed February 10, 1937, so located as to respond to the visible rays of light emanating from the burner flame to close the circuit therethrough, whereby 15 in the event of the failure of the fuel to ignite, the shunt circuit remains open and the heater SH will operate to allow the safety switch SS to open, which will result in a complete shut down of the burner mechanism. 20

In order to ignite the fuel in the nozzle within the predetermined time allowed by the above safety device, an electrical ignition device is provided which in common practice is actuated by the energization of an ignition transformer I. 25 In this embodiment of this invention an ignition switch IS and an ignition heater IH are provided and are connected in circuit on the instrument panel, as shown in Figure 1. The current from the motor switch MS is divided at binding post 10 and part passes through wire 15, through the ignition switch IS, when closed, through binding post 16, through the ignition transformer I and back through binding post 11 to binding post 4 which is connected to wire L'. Part of the current passing through wire 15 from the closed ignition switch IS divides at binding post 16 and passes through wire 17, through the electrical resistance igniter heater IH, the purpose of which will hereinafter be described, through binding post 11 to binding post 4 which is connected to wire L'. If desired the wiring of the control may be revised so as to connect the heater IH in series with the ignition transformer. 30 35

Like the fluid fuel burner ignition control described in this applicant's prior Patent No. 2,140,708, December 20, 1938, this improved control is partially operated by fuel pressure through the response of a Bourdon tube 18 to changes in oil pressure. One end of the Bourdon tube 18 is 40 mounted on a block 19 through which it is connected by a nipple 20, shown in Figures 2, 3 and 5, to a pipe 21 leading from the pressure gauge G of the pressure regulator R interposed in the oil line between the burner nozzle, not shown, and the burner motor operated oil pump OP, as shown in Figure 1. Oil is supplied to the oil pump by pipe P leading from an oil tank located wherever most desirable. 45 50 55

The block 19 is mounted upon the upper left portion of the panel I by screws 22 passing through apertures provided therefor in the block. A base plate 23 is secured to the front of the block 19 by the screws 24 and extends to the right thereof substantially in line with the Bourdon tube 18. The upper lefthand portion of the base plate 23, as shown in Figure 5, is provided with an extension 25 bent at right angles thereto to form an arm to which is attached a bracket 26 supporting depending clips 27 for engaging and supporting the ignition switch IS. The free end of the Bourdon tube 18 terminates in a closed end between the upper portion of the base plate 23 and the panel I. The closed end of the Bourdon tube 18 includes an arm 28 extending axially in 70 75 80 85 90 95 98

prolongation thereof and is pivotally connected at its end to a link 29. The other end of the link 29 mounts a disc 30 adapted to bear upon the apex of a bell crank lever, the lower arm 31 of which is pivotally mounted upon a stud 32 mounted on the rear of the base plate 23, with the other arm 33 terminating in a portion 34 bent at right angles thereto to extend over an indentation 35 formed in the base plate 23. The disc 30 on the 10 end of the link 29 is provided with an axial stud 36 adapted to pass through and travel within a slot 37 formed in the apex body portion of the bell crank lever. The surface of the disc 30 is held in engagement with the body portion of the apex 15 of the bell crank lever by a spring 38 secured at its lower end to the arm 31 adjacent its pivotal point 32. The portion of the base plate 23 spaced apart from the shoulder 35 is provided with an arm 39 bent at right angles thereto adapted to 20 be engaged by one end of an adjustable pin 40 carried in the portion 34 of the arm 33 of the bell crank lever which extends over the shoulder 35 of the base plate and acts as a stop therefor.

The ignition switch IS is preferably a mercury 25 tube switch which is mounted at an angle, as shown in Figures 2 and 5, whereby a pool of mercury is maintained in the lower end. This switch is preferably of the magnetically operated 30 type, such as disclosed in this applicant's prior Patent No. 2,140,708, December 20, 1938, Figure 8, in which one electrode supporting an armature 41 is resiliently mounted so that its contact point 42 will normally be out of engagement with the pool of mercury. The switch is closed by a 35 movable permanent magnet 43 when it is brought adjacent the side of the tube of the ignition switch IS to bring the armature 41 within its field and opened when the magnet is moved away sufficiently to remove the influence of its field 40 upon the armature. The magnet 43 is mounted adjacent the lower end of an operating arm 44, the upper end of which is pivotally mounted upon a stud 45 extending between the base plate 23 adjacent the shoulder 35 and a front plate 46 45 spaced apart from the base plate 23 by posts 47, as shown in Figure 3. The lower extremity of the operating arm 44 mounts a counterweight 48 which will cause the arm, when free, to rotate about its pivot to move the magnet away from 50 the ignition switch to open the ignition circuit. The base plate 23 mounts a stop 49 between the tube of the switch IS and the operating arm 44 to limit its travel and prevent the magnet 43 from bearing against the tube. The upper portion of 55 the operating arm is provided with two shoulders 50 and 51. The shoulder 50 is so formed that it will engage the upper post 47 supporting the front plate 46 to limit the swing of the magnet away from the switch IS and the shoulder 51 is adapted to be engaged by the lower end of the pin 40 60 carried in the portion 34 of the Bourdon tube or pressure controlled bell crank lever 31-33. With the contraction of the Bourdon tube 18 through its connection to the bell crank lever 31-33 the pin 40 is caused to move toward the operating arm 44 until the pin 40 engages the shoulder 51 whereupon movement is imparted to the operating arm toward the switch. When the operating arm 44 engages the stop 49 and further contraction 65 of the Bourdon tube continues, the disc 30 will slide over the bell crank lever 31-33 under the tension of the spring 38 until the axial stud 36 sliding within the slot 37 of the bell crank lever reaches the bottom thereof. With the application 70 of pressure to the Bourdon tube however,

movement of the end of the Bourdon tube in the opposite direction will immediately impart a counter-rotation to the bell crank lever through the clutch formed by the disc 30 and spring 38. Upon increasing the pressure within the Bourdon 5 tube the pin 40 will move to free the operating arm 44 and will continue in its movement until it engages the stop arm 39 whereupon continued movement of the Bourdon tube may occur by reason of the aforementioned clutch arrangement. The slot 37 in the bell crank lever is so arranged as to permit unrestricted movement of the Bourdon tube when subjected to its highest operating pressures. As it is necessary to maintain the ignition switch IS closed for a predetermined time to provide for an ignition period, it is necessary to provide means, independent of the Bourdon tube 18, to hold the magnet 43 in operative position during this period. 10

In order to hold the operating arm 44 in operative position, the side opposite the stop 49 is cut out to form a notch 52 at the bottom of the recess adapted to be engaged by a tooth 53 formed on one end of a gravity operated pawl 54 pivoted at its other end upon a stud 55 mounted between 20 the base plate 23 and the front plate 46 when the arm 44 engages the stop 49. In order to release the operating arm 44, the pawl 54 is rotated about its pivot to lift the tooth 53 from engagement with the notch 52 so that the counterweight 48 25 may rotate the magnet 43 into its inoperative position, as shown in Figure 6. To accomplish this, a strip of thermal or bi-metallic metal 55 is bent about a spool 55a of an electrical resistance heater IH, shown in Figure 1, with the ends of 30 the strip extending therebelow in parallel relation. One end 56 of the strip is secured to a right angular extension 57 of a supporting plate 58 rotatably mounted upon a stud 59 extending into the base plate 23 to the right of and below 35 the stop 39 and supports the spool 55a at right angles to the plate 23. The other end 60 of the strip 55 depends below the end of the pivoted pawl 54. The end of the pawl is provided with a nose 61 adapted to be engaged by the end 60 of the 40 thermal strip when moved in that direction upon energizing the heater IH to lift the pawl 54 to release the operating arm 44. The base plate 23 below the heater IH is provided with an angular extension 62 to mount an adjustable stop 63 45 50 adapted to be engaged by the end 60 of the thermal strip when cold. The heater supporting plate 58 is preferably struck up to form a small bearing surface about its pivot and is pressed into engagement with the surface of the base plate 23 by the free end of a leaf spring 65 55 engaging an extension 64 of the pivot 59, the other end of the spring being secured to the base plate 23 by screw 66. The tension of the spring plate is such that normally, heating and cooling 60 of the bi-metallic metal 55 will cause only the free end 60 to move. The portion of the leaf spring 65 between the spool 55a and the supporting plate 58 preferably mounts a sheet of mica 65 67 or other insulating material.

By proper arrangement of the operative structure and through adjustment at the factory of the pin 40 carried upon the pressure actuated bell crank lever, the magnet operating arm 44 will be caused to close the ignition switch at a predetermined drop in fuel pressure and upon the establishment of a predetermined pressure within the Bourdon tube move the pin from engagement with the arm 44 and at the same time by proper adjustment of the stops 63 with the end 60 of 70 75

the thermostatic strip 55 in engagement therewith and the heater IH energized, the time thereafter required to lift the pawl 54 to release the operating arm 44 may be determined.

- 5 In the operation of fluid fuel burners there are times when for some reason or other, as in the case of a momentary power failure or failure of the burner flame, the normal operation of the burner is interrupted and when this occurs as to 10 cause a cessation of combustion with a subsequent opening of the burner motor circuit it is most desirable that an operative igniter be had when operation is resumed, particularly so should the interruption and resumption of operation 15 take place within a very short time. This invention contemplates meeting these contingencies to the extent that with each opening of the motor switch MS while the thermostatic strip 55 is heated and expanded the ignition control is reset 20 to starting position to provide an ignition period to accompany the re-starting of the burner. In order to accomplish this an arm 68, shown in dotted lines on Figure 2, is mounted on the secondary coil SC of the repulsion relay and so 25 arranged that each time the coil falls the free end of the arm 68 will engage the end 60 of the thermostatic strip 55 to cause the supporting plate 58 to rotate about its pivot and allow the end 60 to be brought into engagement with the stop 63, the 30 same as would be accomplished by the normal cooling of the strip 55.

As above said, a commercial pressure regulator is interposed between the fuel pump and the nozzle of the burner to maintain a substantially 35 constant pressure at the nozzle to atomize the fuel. It is in connection with the use of these regulators employed in all fluid fuel burner mechanisms of the liquid fuel pressure type that this improved form of ignition control proves most 40 advantageous. One type of pressure regulator is provided with a manually adjustable means by which the pressure of the fuel delivered at the nozzle may be varied having a delivery port with means to maintain the port closed up to a pre- 45 determined pressure, usually 60 pounds per square inch, and thereafter allow the delivery of fuel to the nozzle at a pressure not to exceed the pre-determined setting which means also acts to automatically cut off the delivery of fuel whenever 50 the pressure of the fuel drops 25 pounds per square inch below the predetermined setting. Another type of pressure regulator, in addition to the manual adjustment for predetermining the delivery pressure at the nozzle, is provided with 55 means to adjust the pressure at which the cut-off automatically acts in relation to the predetermined pressure. In other words, one form includes a constant differential at which the cut-off automatically acts, while the other form includes 60 means for varying this differential. In these commercial pressure regulators the minimum pressure adjustment is 60 pounds per square inch and the minimum differential is 25 pounds per square inch.

65 In the ignition control disclosed herein, the pin 40 is movable between the shoulder 51 of the operating arm 44 when in operative position with the ignition switch and the fixed arm 39, moving from one limit to the other upon an increase or 70 decrease in pressure of less than the customary 25 pounds, minimum differential maintained in the commercial pressure regulators between the pressure at which fuel is delivered and maintained at the burner nozzle and the pressure at which fuel 75 is cut off. When movement of the pin is limited

by engagement with stop arm 39 or by shoulder 51, when the arm 44 is against stop pin 49, the Bourdon tube clutch mechanism permits continued movement of the Bourdon tube as the pressure within the tube increases or decreases, but immediately upon reversing the pressure condition the movement of the tube is imparted to the pin 40 so that regardless of the operating pressures established by the pressure regulators the ignition switch IS is automatically closed on a 10 drop in pressure less than that required to cause the regulator to cut-off the supply of fuel to the burner nozzle. Since during a normal period of burner operation the ignition switch is opened after the expiration of the ignition time period, 15 the electrical resistance heater 14 being in the circuit controlled by the ignition switch is de-energized and with the cooling of the bi-metallic member 55 the free end 60 thereof moves back to engage the adjustable stop 63. Thus if through 20 some abnormal circumstance the burner flame should be extinguished through loss of fuel pressure it will be preceded by the closure of the ignition switch and as the heater IH has cooled to starting position any resumption of burner 25 operation will be accompanied by a period of ignition.

When the extinguishment of the burner flame has been caused by a loss in pressure resulting from the interruption of the burner circuit, from 30 any cause, before the bi-metallic member 60 returns to starting position against the stop 63, the arm 68, secured to the secondary coil SC will, as the coil falls to its deenergized position, engage the member 60 to cause the supporting bracket 35 therefor to move about its pivot until the arm 60 engages stop 63 and ignition is also assured upon resumption of burner operation when the burner circuit is again restored.

What I claim is:

1. In an electrically operated and controlled fluid pressure burner mechanism including an electrical igniter, an ignition circuit, a switch in the ignition circuit, and means for operating the switch, including a fuel pressure-responsive means, and an electrically operated thermal means co-acting therewith and arranged upon initiation of operation of the burner mechanism to operate the switch a predetermined time thereafter, said means for operating the switch including an override connection to the pressure responsive means allowing unrestricted movement thereof upon pressure changes in excess of those required to operate the switch.

2. In an electrically operated and controlled fluid fuel pressure burner mechanism including an electrical igniter, an ignition circuit, a normally closed ignition switch therein for establishing said circuit upon operation of the burner mechanism, means to open the ignition switch 60 actuated a predetermined time after establishment of the ignition circuit including means to render the opening means partly effective dependent upon the establishment of a predetermined fuel operating pressure and additional 65 means to complete the opening of the switch dependent upon the establishment of the ignition circuit, said means to render the opening means partially effective provided with means allowing a predetermined decrease in pressure after the 70 ignition switch has opened to insure the prompt closing thereof.

3. In an electrically operated and controlled fluid fuel pressure burner mechanism including an electrical igniter, an ignition circuit, a nor- 75

5 mally closed ignition switch therein for establishing said circuit upon operation of the burner mechanism, means to open the ignition switch actuated a predetermined time after establishment of the ignition circuit including means to render the opening means partly effective dependent upon the establishment of a predetermined fuel operating pressure and additional means to complete the opening of the switch 10 dependent upon the establishment of the ignition circuit, said pressure responsive means provided with means to allow unrestricted movement thereof upon pressure changes in excess of those required to operate the switch, said last 15 named means acting upon a predetermined decrease in pressure after the ignition switch has been opened to insure the prompt closing of said switch.

4. In an electrically operated and controlled 20 fluid fuel pressure burner mechanism including an electrical ignition, an ignition circuit and a normally closed ignition switch therein when the burner mechanism is idle, means for operating the switch to open the ignition circuit, 25 means responsive to the pressure of the fluid fuel, a connection between the operating means and pressure responsive means arranged upon the establishment of a predetermined fluid fuel pressure upon initiation of operation of the 30 burner mechanism to partially effect the operation of the switch operating means, and thermally operated means actuated by the passage of current through the normally closed ignition circuit to cause the operating means to open the 35 ignition circuit, said connection having an override means allowing movement of the pressure means upon pressure changes in excess of those required to operate the switch and adapted upon a predetermined decrease in pressure after the 40 ignition switch has been opened to insure a prompt closing of said switch.

5. In an electrically operated and controlled 45 fluid fuel pressure burner mechanism including an electrical ignition device, an ignition circuit and a magnetically operated switch therein, a locking member normally locking the magnetic actuator when the switch is closed, means responsive to the pressure of the fluid fuel arranged to engage 50 said magnetic actuator and close the ignition switch upon a predetermined differential drop in fluid fuel pressure and arranged upon a predetermined increase in fluid fuel pressure upon initiation of operation of the burner mechanism 55 to be disengaged therefrom, and thermally operated means actuated by the continued passage of the current through the normally closed ignition circuit to unlock the magnetic actuator to open the ignition switch.

6. In an electrically operated and controlled 60 fluid fuel pressure burner mechanism including an electrical ignition device, an ignition circuit and a magnetically operated switch therein, a magnetic actuator therefor, means responsive to the pressure of the fluid fuel arranged to act upon said magnetic actuator and close the ignition switch upon a predetermined differential drop in fuel pressure and arranged upon a predetermined increase in pressure upon initiation 65 of operation of the burner mechanism to be inactive upon said means, means delaying the action of the magnetic actuator to open the switch when rendered active by the pressure means including an electrically operated time actuator 70 in the ignition circuit, said pressure responsive

means including an override connection allowing unrestricted movement of the pressure means over its entire operating range beyond the pressures required to operate the switch.

7. In an electrically operated and controlled 10 fluid pressure burner mechanism including an electrical igniter, an ignition circuit, a switch in the ignition circuit, means for operating the switch, means responsive to the pressure of the fluid fuel arranged to act upon said operating 15 means and close the ignition switch upon a predetermined differential drop in fuel pressure and arranged upon a predetermined increase in pressure upon initiation of operation of the burner mechanism to be inactive upon said means, means delaying the action of the operating means to open the switch when rendered active by the pressure means including an electrically operated time actuator in the ignition circuit, 20 said pressure responsive means including an override connection allowing unrestricted movement of the pressure means over its entire operating range beyond the pressures required to operate the switch.

8. In an electrically operated and controlled 25 fluid pressure burner mechanism including an electrical igniter, an ignition circuit, a switch in the ignition circuit, means for operating the switch, a locking member normally locking the operating means when the switch is closed, 30 means responsive to the pressure of the fluid fuel arranged to engage the operating means and close the ignition switch upon a predetermined differential drop in fuel pressure and arranged upon a predetermined increase in fluid fuel pressure 35 upon initiation of operation of the burner mechanism to be disengaged therefrom, and thermally operated means actuated by the continued passage of current through the normally closed ignition circuit to unlock the operating 40 means to open the ignition switch, said pressure responsive means comprising a pressure responsive member, an operator for controlling the switch operating means upon pressure changes, means limiting movement of the operator and a slip connection between the pressure responsive member and operator to allow continued movement of the pressure member beyond the limited movement of the operator.

9. In a fluid fuel burner mechanism, electrically operated means controlling the operation thereof, an electrical igniter, an ignition circuit, a switch in the ignition circuit, and means for operating the switch, including a fuel pressure-responsive means, and an electro-thermal means 50 co-acting therewith and arranged upon initiation of operation of the burner mechanism to operate the switch a predetermined time thereafter, adjustable means for determining the time of action of the electro-thermal means upon said switch means, and means cooperating with the electrically operated means, upon stopping the operation of the burner mechanism, to reset the electro-thermal means substantially to the beginning of its timed period of operation.

10. In a fluid fuel burner mechanism, electrically operated means controlling the operation thereof, an electrical igniter, an ignition circuit, a magnetically operated switch in the ignition circuit, a magnetic actuator therefor, including a 70 fuel pressure-responsive means, and an electro-thermal means co-acting therewith and arranged upon initiation of operation of the burner mechanism to operate the switch a predetermined time thereafter, adjustable means for determining the 75

- time of action of the electro-thermal means upon said switch means, and means cooperating with the electrically operated means, upon stopping the operation of the burner mechanism, to reset 5 the electro-thermal means substantially to the beginning of its timed period of operation.
11. In a fluid fuel burner mechanism, electrically operated means controlling the operation thereof, an electrical igniter, an electrical ignition 10 circuit, a normally closed ignition switch therein for establishing said circuit upon operation of the burner mechanism, means to open the ignition switch actuated a predetermined time after establishment of the ignition circuit including 15 means to render the opening means partly effective dependent upon the establishment of a predetermined fuel operating pressure and additional means to complete the opening of the switch, dependent upon the establishment of the ignition 20 circuit, including an adjustable timed actuator in the ignition circuit adapted to complete the opening of the switch, and means cooperating with the electrically operated means upon stopping operation of the burner mechanism to reset the timed 25 actuator substantially to the beginning of its timed period of operation.
12. In a fluid fuel burner mechanism, electrically operated means controlling the operation thereof, an electrical igniter, an electrical ignition 30 circuit, a normally closed ignition switch therein for establishing said circuit upon operation of the burner mechanism, means for operating the switch, means responsive to the pressure of the fluid fuel arranged to act upon said operating 35 means and close the ignition switch upon a predetermined differential drop in fuel pressure and arranged upon a predetermined increase in pressure upon initiation of operation of the burner mechanism to be inactive upon said 40 means, means delaying the action of the operating means to open the switch when rendered active by the pressure means including an electrically operated time actuator in the ignition circuit, said pressure responsive means including an 45 override connection allowing unrestricted movement of the pressure means over its entire operating range beyond the pressures required to operate the switch, an adjustable timed actuator in the ignition circuit adapted to complete the opening 50 of the switch, and means cooperating with the electrically operated means upon stopping operation of the burner mechanism to reset the timed actuator substantially to the beginning of its 55 timed period of operation.
13. In a fluid fuel burner mechanism, electrically operated means controlling the operation thereof, an electrical igniter, an ignition circuit, a magnetically operated switch therein, a magnetic actuator therefor normally closing the ignition 60 switch when the burner mechanism is idle, fuel pressure responsive means arranged upon initiation of operation of the burner mechanism to partially effect the operation of the switch actuator, an adjustable timed actuator arranged to 65 cause the switch actuator to open the ignition switch upon establishment of the ignition circuit, and means cooperating with the electrically operated means upon stopping the operation of the burner mechanism to reset the timed actuator 70 substantially to the beginning of its timed period of operation.
14. In a fluid fuel burner mechanism electrically operated means controlling the operation thereof, an electrical igniter, an ignition circuit, a switch in the ignition circuit and means for 75

operating the switch including a fuel pressure responsive means and a timed actuator in the ignition circuit co-acting therewith and arranged upon initiation of operation of the burner mechanism to operate the switch a predetermined time thereafter, said pressure responsive means including an override connection allowing unrestricted movement thereof upon pressure changes in excess of those required to operate the switch, adjustable means for determining the time of action of the electro-thermal means, and means cooperating with the electrically operated means upon stopping the operation of the burner mechanism to reset the timed actuator substantially to the beginning of its timed period of operation. 15

15. In a fluid fuel burner mechanism, electrically operated means controlling the operation thereof, an electrical igniter, an ignition circuit, a normally closed ignition switch therein for establishing said circuit upon operation of the burner mechanism, means to open the ignition switch actuated a predetermined time after establishment of the ignition circuit including means to render the opening means partly effective dependent upon the establishment of a predetermined fuel operating pressure and additional means to complete the opening of the switch dependent upon the establishment of the ignition circuit, said pressure responsive means provided with means to allow unrestricted movement thereof upon pressure changes in excess of those required to operate the switch, said last named means acting upon a predetermined decrease in pressure after the ignition switch has been opened to insure the prompt closing of said switch, adjustable means for determining the time of action of the thermally operated means, and means cooperating with the electrically operated means upon stopping the operation of the burner mechanism to reset the thermally operated means substantially to the beginning of its 30 timed period of operation. 35

16. In a fluid fuel burner mechanism, electrically operated means controlling the operation thereof, an electrical igniter, an ignition circuit and a magnetically operated switch therein, a magnetic actuator therefor, a locking member normally locking the magnetic actuator when the switch is closed, means responsive to the pressure of the fluid fuel arranged to engage said magnetic actuator and close the ignition switch upon a predetermined differential drop in fluid fuel pressure and arranged upon a predetermined increase in fluid fuel pressure upon initiation of operation of the burner mechanism to be disengaged therefrom, and thermally operated means actuated by the continued passage of the current through the normally closed ignition circuit to unlock the magnetic actuator to open the ignition switch, adjustable means for determining the time of action of the thermally operated means, and means cooperating with the electrically operated means upon stopping the operation of the burner mechanism to reset the thermally operated means substantially to the beginning of its timed period of operation. 40

17. In a fluid fuel burner mechanism, electrically operated means controlling the operation thereof, an electrical igniter, an ignition circuit and a magnetically operated switch therein, a magnetic actuator therefor, means responsive to the pressure of the fluid fuel arranged to act upon said magnetic actuator and close the ignition switch upon a predetermined differential drop in fuel pressure and arranged upon a pre- 75

determined increase in pressure upon initiation of operation of the burner mechanism to be inactive upon said means, means delaying the action of the magnetic actuator to open the switch when rendered active by the pressure means including an electrically operated time actuator in the ignition circuit, said pressure responsive means including an override connection allowing unrestricted movement of the pressure means over its entire operating range

beyond the pressures required to operate the switch, adjustable means for determining the time of action of the thermally operated means, and means cooperating with the electrically operated means upon stopping the operation of the burner mechanism to reset the thermally operated means substantially to the beginning of its timed period of operation.
